UNITED STATES PATENT OFFICE.

HOSMER HASSAN HENDEE, OF WILBER, NEBRASKA.

DESIGN FOR AN OFFICE-CASTER.

SPECIFICATION forming part of Design No. 32,635, dated May 8, 1900.

Application filed April 10, 1900. Serial No. 12,381. Term of patent 14 years.

To all whom it may concern:

Be it known that I, HOSMER HASSAN HENDEE, a citizen of the United States, and a resident of Wilber, in the county of Saline and State of Nebraska, have invented and produced a new and original Design for an Office-Caster, of which the following is a specification, reference being had to the accompanying drawings, forming a part thereof, in which—

Figure 1 is a side elevation of a caster embodying the features of my design. Fig. 2 is a horizontal section taken substantially on the line 2 2 of Fig. 1, and Fig. 3 is a vertical section through the central portion of the caster.

The invention has relation to designs for casters especially adapted for office use, whereby any one of a number of small articles of desk furniture may be brought before or within convenient reach of the occupant of a desk.

The features of the design consist in the

standard 10, emanating from a base 11, a table 12, loosely supported on the standard and apparently resting on an offset 11^a from the standard, and at the center of the table a hub 12^a is located, separating the table proper from the standard. Knob-like ornaments 13 are arranged around the edge of the table and the table may be otherwise ornamented. The top of the table contains pockets 15 of various shapes, and sundry of these pockets are covered by lids 16. A holder 17, which is of approximately-conical shape, is carried by the table and is independent of the standard 10, while at the upper end of the standard hooks 18 are formed.

I claim—

The design for an office-caster, herein shown and described.

HOSMER HASSAN HENDEE.
